PURSE

Jean Claviez, Paris, France

Application January 25, 1937, Serial No. 122,137.
Renewed June 15, 1938. In France January 31,
1936.

2 Claims. (Cl. 150—37)

The present invention relates to flexible purses made of leather or any other suitable material.

The object of the present invention is to provide a purse of the type which may be reduced, by merely folding it, to a size sufficiently small to be readily inserted into a very small pocket, and which when in open position is large enough to permit an easy selection of any of the various denominations of coins contained therein.

10 I accomplish this object by means of a purse made from a single piece of leather, which is suitably cut and held together by only two rows of stitching, as a consequence of which the article is very easy to make and extremely inexpensive to 15 manufacture.

These and other advantages of the present invention will be clear from the following detailed description of a specific embodiment thereof.

One embodiment of the present invention is 20 hereinafter described in the specification, and illustratively exemplified in the accompanying drawing, in which:

Fig. 1 is a perspective view of the folded purse, ready to be closed or opened;

25 Fig. 2 is an elevational view of the purse, illustrating the same in unfolded position;

Fig. 3 is a view of the blank piece of leather from which the purse is made.

Referring to the drawing, the leather piece 30 from which the purse is to be made is cut in such manner as to form a flap A for closing the purse and a body B₁, B₂ which is to be folded along lines b₁, b₂, d—d, and c—c₁—c₂, the latter being oblique. The edge E₁—b₁—E₂ is V-shaped and, after folding, lines E₁b₁ and E₂b₁ are brought together and connected by a row of stitching, so as to form an inward fold on the lateral side. The edge F₁b₂F₂ is brought together and connected by a row of stitching, the latter running merely along 40 a distance designated H₁b₂H₂, so as to leave angles H₁F₁ and H₂F₂ free. When the purse is folded, the edge formed by d, E₁E₂, d can engage between said free portions H₁F₁ and H₂F₂, as shown in Fig. 1. It will be readily understood that, by pushing the edge b₂H₁F₁F₂ toward the edge E₁E₂b₁, I produce the outward folding of face dcF₁F₂ about c—c₁—c₂, and the inward folding of B₁ and B₂ about line c—d, as shown by Fig. 1.

The end d E₁F₂ d is thus caused to engage 50 F₁H₁H₂F₂.

The coins to be held by the purse are placed in the space limited by the lines E₁E₂b₁—b₁—c—c₁—c₂. It is clear that, in this position of the elements of the purse, they occupy very little space.

55 If the purse is closed and flap A is opened, and

edge b₂c is pulled outwardly, the purse opens widely, coming into the position illustrated by Fig. 2, and there is room enough to permit the fingers to pick up any desired coin.

It will be clear from the above description 5 that the purse, according to the present invention, has the following advantages: It occupies but very little space when closed, although it forms a relatively wide pocket when opened. The manufacture of the present device is very simple, since 10 the whole purse is made from a single piece of leather, with only two seams to be stitched.

Of course, face AB might be twofold, so as 15 to form a pocket adapted to contain papers or banknotes or the like.

In a general manner, while I have, in the above description, disclosed what I deem to be a practical and efficient embodiment of the present invention, it should be understood that I do not 20 wish to be limited as to details, because changes 20 may be made in the arrangement, disposition and form of the parts without departing from the principle of the present invention.

What I claim is:

1. A purse made of a single sheet of a supple 25 material of general rectangular shape having two parallel folds parallel to one side of the sheet, one of said folds being located in the middle part of the sheet and the other along one side of said sheet, the edge of said last mentioned side of the sheet forming an angle having its opening turned outwardly and its apex located upon said second mentioned fold, the two sides of said angle being sewn together, a third fold extending at right angles to the two first mentioned folds and starting from said apex, and two folds starting both 30 from the intersection of the first and third folds with each other and extending respectively to the ends of the other side of said sheet that is parallel to the two first mentioned folds, the two 35 halves of said last mentioned side being sewn together from said third mentioned fold to a small distance from said ends of said last mentioned side, whereby in the folded position of the purse, said last mentioned side is brought between the two other sides of the sheet which extend at right angles to the two first mentioned folds, and means 40 for securing the parts together in the closed position of the purse.

2. A purse according to claim 1 in which the 50 last mentioned means consist of a flap integral with said sheet and forming an outward projection of the part of the sheet extending between the two first mentioned folds.

JEAN CLAVIEZ. 55
